(57) **CLAIM**

The ornamental design for a solar cell wafer, as shown and described.

DESCRIPTION

FIG. 1 is a front elevational view of a solar cell wafer;
FIG. 2 is a rear elevational view thereof;
FIG. 3 is a top plan view thereof, the bottom plan view being a mirror image of the top plan view;

FIG. 4 is a right side elevational view thereof, the left side elevational view being a mirror image of the right side elevational view;

FIG. 5 is an enlarged view of callout box 5 from FIG. 1; and,
FIG. 6 is an enlarged view of callout box 6 from FIG. 2.
The dot-dash broken lines form no part of the claimed design.
